UNITED STATES PATENT OFFICE.

WILLIAM W. PHILLIPS, OF ST. LOUIS, MISSOURI, ASSIGNOR TO BUFFUM TOOL COMPANY, OF LOUISIANA, MISSOURI, A CORPORATION OF MISSOURI.

TYPE-WRITING MACHINE.

1,142,363.

Specification of Letters Patent. Patented June 8, 1915.

Application filed September 21, 1914. Serial No. 862,739.

To all whom it may concern:

Be it known that I, WILLIAM W. PHILLIPS, a citizen of the United States, residing at St. Louis, Missouri, have invented a certain 5 new and useful Improvement in Type-Writing Machines, of which the following is a full, clear, and exact description, such as will enable others skilled in the art to which it appertains to make and use the same.

10 This invention relates to typewriting machines, and particularly to machines of the design in which the carriage is provided at one end with a device that the operator grasps to actuate the line-spacing mechanism and to move the carriage laterally of 15 the machine back to its starting position. In some typewriting machines this combined line-spacing and carriage-restoring device is located at the left hand end of the carriage, 20 and in other typewriting machines it is located at the right hand end of the carriage. Consequently, some operators prefer one type of machine merely because it is more convenient to use the left hand to operate the 25 line-spacing mechanism and restore the carriage to starting position, and other operators prefer the other type of machine because they find it more convenient to use the right hand to operate the line-spacing mechanism and to restore the carriage to starting 30 position.

The main object of my invention is to provide a typewriting machine which is so designed that the operator can use either the 35 right or the left hand to operate the line-spacing mechanism and restore the carriage to starting position, the carriage of the machine being equipped with two separate and distinct devices located adjacent the opposite ends of the carriage for effecting these 40 operations.

Another object of my invention is to provide an attachment for an Underwood typewriting machine that can be applied to same 45 easily, so as to enable the operator to use the right hand as well as the left hand to operate the line-spacing mechanism and move the carriage laterally back to starting position.

Other objects and desirable features of 50 my invention will be hereinafter pointed out.

Figure 1 of the drawings is a top plan view of a portion of the carriage of an Underwood typewriting machine equipped 55 with my attachment; Fig. 2 is a transverse

vertical sectional view taken on the line 2—2 of Fig. 1, looking in the direction indicated by the arrow; and Fig. 3 is a vertical sectional view taken on the line 3—3 of Fig. 1.

Referring to the drawings which illustrate the preferred form of my invention, A designates the carriage of the machine, 1 designates the feeding pawl that co-operates with the ratchet wheel 2 on the platen shaft to form the line-spacing mechanism, and 3 60 designates the bell crank lever at the left hand end of the carriage A that the operator grasps to actuate said line-spacing mechanism and to move the carriage laterally back to starting position, said lever 3 being pivotally mounted on the carriage and provided at its front end with an upwardly projecting finger piece 3^a. The parts above mentioned are of the usual construction embodied in 65 the standard Underwood typewriting machine now in general use.

In order that an operator may use her right hand as well as her left hand to actuate the line-spacing mechanism previously referred to, and also move the carriage laterally back to starting position, I have equipped the carriage A with a device B provided with a finger piece 4 that is located at the right hand end of the carriage, said 70 device B being so constructed and arranged 75 that it will actuate the lever 3 when the operator moves said device to the right. The device B preferably consists of a bar arranged at the rear of the front cross member 5 of the carriage A, and on the left hand end of said bar is a projection 6 that engages the bell crank lever 3 and actuates same when said bar is moved to the right, looking at Fig. 1. The bar B is mounted on the carriage 80 in such a manner that it can move relatively to the carriage a sufficient distance to actuate the bell crank lever 3, but after said lever has completed its feeding stroke the carriage A will start to move laterally in the direction in which the operator is moving 85 the bar B. When the operator releases the bar B or removes her finger from the finger piece 4 at the right hand end of said bar, the spring 6^a that forms part of the line-spacing mechanism exerts pressure on the lever 3 and restores it to normal position, and said lever, in turn, restores the bar B to 90 normal position.

Any suitable means may be employed for 95 mounting the bar B on the carriage of the 100

105

110

machine, the means herein shown consisting of a bolt or stud 7 in the front cross member 5 of the carriage that projects through a horizontally disposed elongated slot 8 in the right hand end of the bar, and a guide or strap 9 at the left hand end of the carriage, through which the bar B passes, as shown in Fig. 2, said strap 9 being carried by a removable plate 10 on the carriage under which the forwardly projecting arm of the lever 3 passes. The carriage of the standard Underwood machine is equipped with a removable plate similar to the plate 10 of the machine herein shown, except that it is not provided with a guide or strap 9 and the front cross member 5 of the carriage of a standard Underwood is also provided with a screw located in the same position as the bolt 7 of the machine herein illustrated. Consequently, in applying my attachment to an Underwood machine, it is not necessary to form any additional holes in the carriage or cut the carriage, but, on the contrary, it is only necessary to substitute a bolt 7, a plate 10 of the particular design herein shown and arrange the bar B in operative position. The intermediate portion of the bar B is bent downwardly at 11, as shown in Fig. 2, so that it will not interfere with the envelop guide 12 that is usually formed on the rear side of the front cross member of the carriage of an Underwood machine.

While I have herein illustrated my invention applied to an Underwood machine, I wish it to be understood that the invention is not limited to any particular type or make of typewriting machine, or to a machine in which the device that actuates the line-spacing mechanism and restores the carriage to starting position is located at the left hand end of the carriage, for my broad idea consists in a typewriting machine in which the carriage is provided with two separate and distinct means, located at the right and left hand ends of the carriage for operating the line-spacing mechanism and for restoring the carriage to starting position, so that the operator can use either hand for performing these operations.

Having thus described my invention, what I claim and desire to secure by Letters Patent is:

1. In a typewriting machine provided with a line-spacing mechanism and a lever for operating the same arranged adjacent one end of the carriage of the machine, a shiftable bar extending across the front portion of said carriage, one end of said bar being supported adjacent said lever by means of the end frame of the carriage and provided with a projection that lies behind said lever, the opposite end of said bar being provided with a handle or finger piece and supported on the front portion of said carriage by means of a slot and pin connection. 60

2. In a typewriting machine, a line-spacing mechanism and a lever for actuating the same arranged at one end of the carriage, a shiftable bar having one end slidably mounted on the end frame of the carriage adjacent said line-spacing mechanism, a guide on said carriage for preventing lateral displacement of said bar, a projection on one end of said bar that is adapted to engage said lever, a finger piece on the opposite end of said bar, and a slot and pin connection between said bar and said carriage adjacent said finger piece. 75

3. An attachment for an Underwood typewriting machine, consisting of a bar that is adapted to be reciprocatingly mounted on the front cross member of the carriage of the machine for operating the lever on said carriage that is used for actuating the line-spacing mechanism, and removable devices that are adapted to be connected to the carriage for supporting and guiding said bar, said bar being provided at one end with a finger piece and at its opposite end with a portion for engaging said lever when the bar is shifted in one direction. 90

In testimony whereof I hereunto affix my signature in the presence of two witnesses, this 17 day of September 1914.

WILLIAM W. PHILLIPS.
